UNITED STATES PATENT OFFICE

HERMAN BETKE, OF DENVER, COLORADO

STEAM BOARD

Application filed October 24, 1929. Serial No. 402,047.

An object of this invention is to provide an improved construction of steam board.

A further object of the invention is to provide improved means for establishing and maintaining a relatively high temperature in the steaming buck of a steam board prior to and during the steaming operations.

A further object of the invention is to provide improved means for exhausting steam from the steaming buck of a steam board.

A further object of the invention is to provide an improved construction of operating head in a steam board.

A further object of the invention is to provide an improved system of steam connections and passages in and with the operating head of a steam board.

A further object of the invention is to provide improved means in a steam board whereby a single steam circuit may be employed through suitable valve controls to operate the steaming buck of said board, to preheat said buck and to exhaust steam and air from and through said buck.

A further object of the invention is to provide improved control means for a steam board.

A further object of the invention is to provide improved valve-operating means in and for a steam board.

A further object of the invention is to provide an improved system of pedal control means for a steam board.

A further object of the invention is to provide improved means for the simultaneous operation of a pair of separate valves in a steam board.

A further object of the invention is to provide improved spring-operated means for normally retaining the valves of a steam board in closed position.

A further object of the invention is to provide improved spring means operable to normally retain a plurality of valves in closed position in a steam board and yieldable to

permit selective opening of any one or any combination of said valves.

My invention consists in the construction, arrangement and combination of elements hereinafter set forth, pointed out in my 50 claims and illustrated by the accompanying drawings, in which—

Figure 1 is a side elevation of my improved steam board as assembled and connected for practical use. Figure 2 is a plan view, on an enlarged scale and partly in section, of the operating head and steaming buck of the improved board; a portion of the buck being broken away to conserve space. Figure 3 is a vertical, longitudinal section axially 55 of the steaming buck and operating head, on the same scale as Figure 2. Figure 4 is a cross section transversely of the operating head on the indicated line 4—4 of Figure 2. Figure 5 is a side elevation of the operating 60 head and a portion of the steaming buck, a portion of said head being broken away to expose interior construction. Figure 6 is a cross section transversely of the steaming buck on the indicated line 6—6 of Figure 5. 65

Figure 7 is a cross section taken through the operating head on the indicated line 7—7 of Figure 4. Figure 8 is a plan view of the base of the improved board taken through the supporting pedestal on the indicated line 75 8—8 of Figure 1. Figure 9 is an end elevation of the showing of Figure 8. Figure 10 is a longitudinal, axial section through a modified construction of steaming buck. Figure 11 is a cross section taken on the indicated line 11—11 of Figure 10. Figure 12 is a cross section taken on the indicated line 12—12 of Figure 1.

In the construction of the improvement as shown, a suitable stand support for a steam board is illustrated as comprising a base plate 85 15 adapted to rest on a floor or similar surface and a pedestal 16 fixed to and rising from said plate 15, said pedestal preferably being substantially perpendicular to the plane of 90

said plate and, for convenience, being curved approximately as shown in Figure 1. The plate and pedestal illustrated and described may well be formed as an integral casting or molding, but may obviously be constructed in any manner and form suitable to their function. The upper end of the pedestal 16 is shaped to conform to and fit snugly within a side-opening recess 17 formed in the lower 5 portion of an integral operating head 18, whereby said head 18 may be mounted on and supported above said pedestal, a web of said head 18 extending across one side of the upper end of said pedestal and being formed 10 with a hole 19 in registering relation with a similar hole in and through said upper end of the pedestal to receive a bolt 20 extending through said web and the upper end of said pedestal to firmly clamp and hold said head 15 18 to and on said pedestal. To prevent relative rotation between the head 18 and pedestal 16 about the bolt 20 as a pivot, a second hole 21 is formed in the lower portion of said head 20 perpendicular to the hole 19 to receive a bolt 25 or screw 22 engaging in or bearing against the rear face of said pedestal. A relatively 30 long hollow casing or shell 23, perforated on its upper surface and preferably tapered to a reduced end portion in elevation and plan, is 35 provided with a closed outer end and is rigidly secured at its open inner end, preferably by welding or brazing, to one face of the head 18, so that said shell 23 extends in substantially a horizontal plane laterally from said 40 head in parallel relation with and above the longer axis of the base plate 15. The shell 23 is preferably substantially oval in section and for practical purposes is preferably covered with a porous pad 24 and a fabric cover 45 25, said pad and cover being formed of material through which steam may readily pass. An imperforate tube 26, having a closed outer end, is mounted longitudinally within and in spaced relation with the inner walls of the 50 shell 23, the open inner end of said tube 26 being received in threaded or other suitable sealed engagement in a bore formed in the head 18 and opening into the interior of the shell 23, the closed end of the tube 26 extending 55 adjacent the closed end of the shell 23, thus forming non-communicating compartments within said tube and said shell. A bore 27 is formed in and through the head 18 in axial alignment and concentric with the tube 26, the inner end of said bore serving as a seat 60 for a tube 28, open at both ends and longitudinally disposed within the tube 26, spaced from the inner walls of said latter tube and extending adjacent the closed end of said tube 26, a pressure pipe 29, leading from any suitable source of steam (not shown) being seated in and communicating with the outer end of the bore 27, so that steam passing through 65 the pressure pipe 29 is discharged through the bore 27 and tube 28 into the interior of the 70 imperforate tube 26 adjacent its outermost end, filling the space between the tubes 26 and 28 and heating these elements of the device. In order to provide for continuous circulation of steam in and through the tubes 26 and 28, a return steam line 30 is mounted at one end in the head 18 spaced from and below the pressure pipe 29 and connects said head with the return port of the source of steam, a passage 31 formed in the head 18 75 providing communication between said return pipe and the space between the tubes 26 and 28, so that steam discharged from the tube 28 adjacent the outer end of the tube 26 moves rearwardly toward the head 18 80 through the space between said tubes and is returned to the source of steam through the passage 31 and return pipe 30, the cross sectional area of the passage 31 being less than that of the tube 28 to insure that the space 85 between the tubes 26 and 28 is at all times filled with steam under a degree of pressure. Valves may be installed in either or both of the pipes 29 and 30 to control the passage of steam therethrough, but when the device is 90 arranged for practical use it is intended that said pipes 29 and 30 shall be free and unobstructed and that steam shall circulate freely and continuously through said pipes, the 95 passage 31 and the tubes 26 and 28, to the end 100 of heating the recited elements and consequently heating the shell 23 and head 18 as well. The elements of the device above described constitute the heating unit and the shell 23 forms the steaming buck on which the 105 fabric or garment to be steamed is supported. A vertical, downwardly-opening bore 32 is formed in the head 18 at one side of and spaced from the bore 27 and communicates with said latter bore through a steam passage 33 formed in the head 18. The upper, inner end of the bore 32 is provided with a downwardly-extending annular rib 34 through which a steam passage 35 extends 110 upwardly and forwardly of the head 18 to connect the bore 32 with the space between the shell 23 and tube 26, thus providing means whereby steam may pass from the bore 27 through the passage 33, upper end of the bore 32 and passage 35 to the interior of the 115 shell 23. Since continuous flow of steam into the shell 23 is unnecessary and would result in excessive waste of steam, valve means are provided to normally interrupt said flow, said 120 valve means comprising a valve stem 36 positioned axially of the bore 32, slidably mounted in and through a packing gland 37 closing the lower end of said bore and projecting below said gland to terminate in a clevis 38 adjustably threaded on the lower end of the 125 stem. The upper end of the stem 36 is formed as a head 39 on which is removably and replaceably mounted a valve disc 40 substantially filling the bore 32 and formed with an annular recess in its upper face wherein is 130

seated a disc of yielding material 41 in opposition to and adapted to seat against and form a seal with the annular rib 34 when the valve assembly is pressed upwardly against said rib, as shown in the drawings. It is obvious that with the valve assembly in the position shown no steam can pass through the passage 33 and into the passage 35, and leakage of steam from the bore 32 is prevented by the gland 37, but when the valve assembly is moved downwardly and the disc 41 is unseated from the rib 34, a continuous passage is provided for the steam between the bore 27 and interior of the shell 23, as above set forth. 5

Spring means are provided to hold the valve assembly in normally closed position and will be hereinafter more specifically described, as will also be the pedal means operable to open the valve assembly. In like manner, a vertical, downwardly-opening bore 42 is formed in the head 18 parallel with and spaced on the opposite side of the bore 27 from the bore 32 and communicates with said bore 27 through a steam passage 43 formed in said head. The 10 inner end of the bore 42 is provided with an annular rib 44 identical with the rib 34 of the bore 32 against which is normally seated the sealing disc 41' of a valve assembly identical with that above described for the bore 32, said 15 valve assembly in the bore 42 comprising a stem 36', having a head 39', slidingly mounted through a packing gland 37' in the lower end of said bore 42 and carrying the valve disc 40' on its upper headed end and an adjustable 20 clevis 38' on its lower end. A steam passage 25 45 extends from the inner end of the bore 42 upwardly through the rib 44 and within the head 18 where said passage is curved forwardly and then downwardly to communicate with the upper end of a relatively large, downwardly-opening bore 46 spaced from and parallel with the bore 42, an exhaust pipe 47 being seated in the lower end of the bore 46 and leading to any suitable point of discharge, 30 such as a drain or receptacle. Adjacent and forwardly of the bore 46, a bore 48 is provided in the head 18 and a steam passage 49 connects the inner end of the bore 48 with the space between the shell 23 and tube 26, communication between the inner ends of the 35 bores 46 and 48 being had through a passage 50 therebetween. The inner end of the bore 48 is formed as a seat for a plain valve 51 carried by a stem 52 mounted for vertical reciprocation through a packing gland 53 closing the lower end of said bore, the lower end of said stem 52 extending below the gland 53 and being provided with an adjustable clevis 54 similar to the clevises 38 and 38'. With the 40 construction above described, it is obvious that when the valves in the bores 42 and 48 are closed against their respective seats, no steam may pass from the bore 27 to the bore 46, nor may steam or air pass from within the shell 23 to the bore 46; however, when the 45 valves in the bores 42 and 48 are both opened, steam from the bore 27 may move along the passage 43 into the bore 42 and thence through the passage 45 from whence it is discharged as a jet into the bore 46, which jet 70 action produces a lowered pressure in the upper end of the bore 46 and effects a suction action through the passage 50, bore 48 and passage 49 to withdraw steam from the interior of the shell 23 for discharge through the exhaust pipe 47 together with the steam from the jet. The suction action above described causes air to be drawn through the material being treated on the buck and into the interior of the shell 23, thus completely 75 removing any steam from said material and thoroughly drying and cooling the same. 80

From the foregoing description it is obvious that the valve 51 should be closed when the valve assembly in the bore 32 is opened 85 for the steaming operation, thus preventing waste of steam through the exhaust pipe 47, and that said valve 51 should operate simultaneously with the valve assembly in the bore 42 for the desired suction effect. Any suitable arrangement may be provided for the selective control of the valves employed in the device, a preferred and most convenient form of pedal control, leaving the hands of the operator free for manipulation of the material being treated, being illustrated and hereinafter described. Spaced supports 55 rise from the rearward end of the base plate 15 on opposite sides of the longitudinal median line thereof and support a pivot pin 100 56 in horizontal position transversely of and above said base plate. Levers 57, 58 are pivotally secured at one end each to the pin 56 and extend in parallel, adjacent relation longitudinally of the base plate 15 and through an opening formed in the lower end of the pedestal 16, to support adjacent pedal members 59 and 60, respectively, on their free forward ends above said base plate. The lever 57 is preferably longer than the lever 58 105 and inclined throughout the major portion of its length below the position of the lever 58, both of said levers being curved upwardly adjacent their free ends to permit the pedals 59 and 60 to normally lie in a common plane 110 and in substantial alignment longitudinally of the base plate. The base plate 15 is also preferably slotted beneath the lever 57 to give added range of movement to said lever and a stop 61 is formed on said base plate beneath 115 the pedal 60 to engage said pedal when the same is depressed and arrest its downward movement to prevent its contacting with and operating the lever 57. The clevises 38' and 54 are connected for simultaneous operation 120 by a yoke 62, the mid-portion of said yoke being pivotally connected with the lever 58 by means of a pull rod 63, so that, when the pedal 60 is depressed, a pull is exerted on the yoke 62 through the rod 63 which serves to 125

simultaneously unseat and open the valves in the bores 42 and 48. In like manner, the clevis 38 is pivotally connected with the lever 57 by means of a pull rod 64, so that, when the pedal 59 is depressed, a pull is exerted on the valve stem 36 through the rod 64, which serves to unseat and open the valve in the bore 32. A stud 65 extends rearwardly from the pedestal 16 on the longitudinal line 10 of the base plate 15 and above the levers 57 and 58, said stud terminating in an apertured end between the pull rods 63 and 64 and serving as a guide for the free lower end of a pin 66 vertically supported between said rods 63 and 64 by and pivotally depending from a yoke 67 carried in and bridging between registering apertures in said rods, said pin 66 forming the slidable core for an expansive coil spring 68 confined between the 20 enlarged upper end of said pin and the rearward end of the stud 65. From the construction shown and described, it is apparent that the expansive force of the spring 68 is exerted against the yoke 67 in an upward direction to normally lift the rods 63 and 64 and hold the valves in the bores 32, 42 and 48 in closed position, at the same time lifting the levers 57 and 58 to bring the pedals 59 and 60 into operative position, depression of 25 either pedal operating its respective pull rod and valve or valves against the pressure of the spring 68 without disturbing the other pedal or its connections. Since no good purpose is served by opening the valve in the bore 32 when the valves in the bores 42 and 48 are open, and vice versa, it follows that the pedals 59 and 60 need never be operated simultaneously, hence the operator can control the apparatus with but one foot and 30 by simply shifting from one pedal to the other, a distance of but a few inches.

In the modification shown in Figures 10 and 11, the operating head, pedestal and control system is essentially the same as above set forth, the only difference being in the construction and arrangement of the elements comprising the steaming buck and heating chamber. In the figures last above noted, the tube 26 is replaced by a tubular extension 26' formed integrally with the head 18 into which the bore 27 opens directly and the tube 28 is replaced by a tube 28' communicating directly with the return pipe 30 through the passage 31, said tube 28' being open at both ends as was the tube 28 and the extension 26' being closed at its outer end and imperforate, so that steam from the bore 27 is carried to the outer end of the extension 26' and thence returned through the tube 28' and returned 50 through the pipe 30, thus reversing the circulation of steam within the heating chamber as formerly described. The extension 26' is stepped down below the top of the head 18 and a thin metal plate 23', perforated as was 55 the shell 23, is substituted for said shell and

spaced above the extension 26', said plate being curved to contact with said extension and be marginally sealed thereto, the passages 35 and 49 obviously opening into the space between the plate 23' and extension 26'. 70

Any suitable table or other means for supporting the overhang of material being treated may be employed with the machine, a convenient and preferred form being illustrated as comprising a troughed table 69, 75 having upwardly diverging side portions, said table being positioned beneath the steaming buck and supported at one end by suitable clamping means 70 fixed to said table and engaging an eye 71 carried by the pedestal 16, 80 the outer end of the table being provided with suitable legs 72 engaging the floor or other surface supporting the steam board. 85

In the practical operation of the improved steam board, steam under pressure is circulated continuously within and through the heating chamber formed by the tubes 26 and 28 or the elements 26' and 28', the steam in each case entering the heating chamber at one end and escaping therefrom at the other end, 90 so that an even temperature is at all times maintained in the heating chamber and steaming buck, said temperature being high enough to prevent condensation of any steam and insure against wetting of the material to be treated. The material to be treated having been placed over the steaming buck, the pedal 59 is depressed to open the valve in the bore 32 thereby admitting steam from the pressure line into the shell 23, from whence it escapes, the valve 51 being closed, through the perforations in said shell to produce the desired effect on said material. The steaming operation is continued as long as may be desired, then the valve in the bore 32 is permitted to 100 close and the pedal 60 depressed to open the valves in the bores 42 and 48, producing the jet effect in the bore 46 resulting in a suction effect through the shell 23 which operates to withdraw steam from said shell and to draw 105 air through the material being treated, into said shell, thereby thoroughly removing the steam trapped in said material and drying and cooling the said material, during all of 110 which operations the heating chamber continues to function. 115

Since many changes and modifications of the form and construction of the elements comprising the improvement may be had without departing from the spirit of the invention, I wish to be understood as being limited solely by the scope of the appended claims rather than by the illustrative showing and foregoing description. 120

I claim as my invention—

1. A steam board comprising an operating head, a steaming chamber supported by and projecting laterally from said head, a heating unit within and sealed from said steaming chamber, a steam line communicating through 125

5 said head with said heating unit, a steam passage within said head between said steam line and the interior of said steaming chamber and valve means in said head and intersecting said steam passage for selective control of the flow of steam therethrough.

10 2. A steam board comprising an operating head, a steaming buck supported by and projecting laterally from said head, a heating unit within and sealed from said steaming buck, a steam line communicating through said head with said heating unit, a valve chamber in said head adjacent and spaced from said steam line, a passage between said steam line and valve chamber, a second passage between said valve chamber and the space between said heating unit and steaming buck and a valve in said chamber for selective control of the flow of steam through said passages.

15 20 3. A steam board comprising an operating head, a perforated steaming buck supported by and projecting laterally from said head, a heating unit within and sealed from said steaming buck, means including a steam line and a steam return line communicating through said head with said heating unit for the continuous circulation of steam therethrough, a valve-controlled steam passage in said head connecting said steam line with the space between said heating unit and steaming buck, whereby steam may be optionally circulated within and through said steaming buck, a second valve-controlled steam passage in said head connecting said steam line with an exhaust jet and a valve-controlled passage between the discharge bore of said jet and the space between said heating unit and steaming buck, whereby the suction effect of said jet may operate to exhaust steam and air from the interior of said steaming buck.

25 45 4. A steam board comprising a base, a pedestal rising from said base, an operating head supported by said pedestal, a perforated steaming buck supported by and projecting laterally from said head, a heating unit within and sealed from said steaming buck, means including a steam line and a steam return line communicating through said head with said heating unit for the continuous circulation of steam therethrough, means in said head including a steam passage and a valve normally obstructing said passage for the optional circulation of steam from said steam line within and through said steaming buck, an exhaust pipe leading from said head, a steam jet leading from said steam line through a normally-closed valve to discharge into said exhaust pipe, a suction passage communicating through a normally-closed valve with said steaming buck and said exhaust pipe, and pedal means carried by said base for independent, selective operation of the valve controlling the inlet of steam to the steaming buck and simultaneous opera-

tion of the valves controlling the steam jet and suction passage.

5. In a steam board having a pedestal base, an operating head supported on and by said base, a perforated steaming buck supported by and projecting laterally from said head, a heating unit in and sealed from said buck and means including a steam line and a steam return line communicating through said head with said heating unit for the continuous circulation of steam therethrough, means for the optional circulation of steam within and through said steaming buck, said means comprising a valve chamber in said head adjacent and spaced from said steam line, a passage connecting the inner portion of said valve chamber with said steam line, a valve seat on the inner end of said valve chamber, an axially-movable valve member in said chamber normally spring held in sealing relation with said valve seat, a passage opening through said valve seat and normally closed by said valve member and communicating with the interior of said steaming buck, means for sealing the outer end of said valve chamber against the escape of steam therefrom and pedal means carried by said base and operatively connected with said valve member whereby the latter may be moved axially from its seat to permit the passage of steam from said steam line to the interior of said steaming buck.

10 6. In a steam board having a pedestal base, an operating head supported on and by said base, a perforated steaming buck supported by and projecting laterally from said head, a heating unit in and sealed from said steaming buck and means including a steam line and a steam return line communicating through said head with said heating unit for the continuous circulation of steam therethrough, a pair of steam passages communicating with said steam line within said head, one of said passages leading through a normally spring-closed valve to a connection with the interior of said steaming buck, the other of said passages leading through a normally spring-closed valve to a steam jet within said head, an exhaust pipe in said head to receive the discharge from said jet, a suction passage leading from the interior of said steaming buck through a normally spring-closed valve to said exhaust pipe adjacent said jet and separate pedal means carried by said base for independent actuation of the valve controlling the inlet of steam to said steaming buck and simultaneous actuation of the valves controlling the steam jet and suction passage.

15 7. In a steam board having a pedestal base, an operating head supported on and by said base, a perforated steaming buck supported by and projecting laterally from said head, a heating unit in and sealed from said steaming buck, means including a steam line and

a steam return line communicating through said head with said heating unit for the continuous circulation of steam therethrough and valve-controlled means communicating with said steam line for optional circulation of steam within and through said steaming buck, valve-controlled means in said head whereby steam may be exhausted from and air drawn within and through said steaming buck, said means comprising an exhaust pipe leading from said head, a steam jet operatively connected through a normally spring-closed valve with said steam line and discharging into said exhaust pipe, a passage 10 connecting the interior of said steaming buck through a normally spring-closed valve with said exhaust pipe adjacent said jet, a yoke connecting the valves controlling said steam jet and said latter passage for simultaneous 15 actuation, a pedal hinged to and supported by said base and a pull rod operatively connecting said pedal with said yoke.

8. In a steam board having a base, an operating head supported on and by said base and a perforated steaming buck supported on and projecting laterally from said head, a hollow chamber having one open and one closed end disposed longitudinally within and sealed from said steaming buck and supported at its open end by said head, an open-ended pipe longitudinally within said hollow chamber and supported by said head with its remote end adjacent the closed end of said chamber, a bore longitudinally of said head and communicating with said open-ended pipe, a steam line operatively connected with said bore, a return steam line connected with said head adjacent and sealed from said bore, a passage in said head connecting the interior of said chamber with said return steam line, a steam passage connecting said bore through a normally spring-closed valve with the interior of said steaming buck, an exhaust pipe leading from said head, a steam jet in said head in position to discharge into said exhaust pipe, a steam passage connecting said bore through a normally spring-closed valve with said steam jet, a suction passage connecting the interior of said steaming buck through a normally spring-closed valve with said exhaust pipe adjacent said steam jet and separate pedal means carried by said base for independent actuation of the valve controlling the inlet of steam to said steaming buck and simultaneous actuation of the valves controlling said steam jet and suction passage.

9. In a steam board having a pedestal base and an operating head supported on and by said base, a relatively long, hollow chamber supported by and projecting laterally from said head, an open-ended pipe supported by said head within and longitudinally of said chamber, the free end of said pipe opening adjacent the closed outer end of said cham-

ber, a steam line and a steam return line operatively connected through bores in said head with said hollow chamber and pipe, whereby steam may be continuously circulated in and through said pipe and chamber, a perforated shell spaced from and adjacent said hollow chamber, a steam passage in said head connecting the interior of said shell through a normally spring-closed valve with said steam line, an exhaust pipe leading from said head, a steam jet in said head in position to discharge into said exhaust pipe, a steam passage in said head connecting said jet through a normally spring-closed valve with said steam line, a suction passage in said head connecting the interior of said shell through a normally spring-closed valve with said exhaust pipe adjacent said jet and separate pedal means carried by said base for independent actuation of the valve controlling the inlet of steam to said shell and simultaneous actuation of the valves controlling said steam jet and suction passage.

10. In a steam board having a pedestal base, an operating head supported on and by said base, a hollow heating unit supported by and projecting laterally from said head, a perforated steaming chamber adjacent and sealed from said heating unit and means including a steam line and a steam return line communicating through said head with said heating unit for the continuous circulation of steam therethrough, valve-controlled means in said head for the optional circulation of steam from said steam line within and through said steaming chamber and separate valve-controlled means in said head and operable from said steam line to withdraw steam and air from said steaming chamber.

11. In a steam board having a base, a heating unit comprising a pair of tubular elements and a perforated steaming chamber adjacent and sealed from said heating unit, an operating head carried by said base and supporting said heating unit and steaming chamber, a bore in said head communicating with one of the tubular elements of said heating unit, a steam line operatively connected with said bore, a steam return line engaging in said head, a passage in said head connecting the other of the tubular elements of said heating unit with said steam return line, a passage in said head connecting said bore with said steaming chamber, a valve carried by said head and normally closing said latter passage, means carried by said base and operatively connected with said valve whereby the latter may be moved to open said passage for the optional circulation of steam within said steaming chamber, an exhaust pipe leading from said head, a steam jet in said head and discharging into said exhaust pipe, a passage in said head connecting said bore with said steam jet, a valve carried by said head and normally closing the passage to

said jet, a suction passage connecting the interior of said steaming chamber with said exhaust pipe adjacent said jet, a valve carried by said head and normally closing said suction passage and means carried by said base and operatively connected with the valves controlling said jet passage and said suction passage whereby said valves may be simultaneously moved to open both said passages and withdraw steam and air from said steaming chamber through the suction effect of steam escaping from said jet.

Signed at Denver, in the county of Denver and State of Colorado, this eighteenth day of May, 1929.

HERMAN BETKE.
